Inventor:
George Schustarich,
by Robert Burns Atty

UNITED STATES PATENT OFFICE.

GEORGE SCHUSTARICH, OF CHICAGO, ILLINOIS.

STRAP WRENCH.

Application filed December 7, 1925. Serial No. 73,669.

This invention relates to that type of wrenches in which a pliable strap or band is adapted to frictionally embrace the article to be turned, or to be held against a turning movement, and more especially to that form of wrenches used in opening household fruit and like jars having closure caps which screw into place.

The object of the improvement is to provide a simple and substantial structural formation and combination of the wrench parts adapted to provide as extended, even and strong holding grip upon the perimeter of an article to effect a forcible turning of the same in a clockwise, or in a counter-clockwise, direction, without marring a highly finished and smooth surface of the part thus engaged, and with a minimum liability to breakage when such part is formed of glass or like frangible or delicate material, all as will hereinafter more fully appear.

In the accompanying drawing:—

Fig. 1, is a perspective view of the wrench in place upon the closure cap of a household jar.

Fig. 2, is a perspective view of the wrench parts in a detached condition.

Fig. 3, is a detail view illustrating a modified connection between the strap and lever of the wrench.

Like reference numerals indicate like parts in the different views.

In the present structure, the article engaging means comprises a pliable strap or band 1 of fabric, leather or other suitable material, adapted to encircle and frictionally engage the perimeter of the article operated on, the frictional engagement being attained by a handle or lever 2 to which the respective ends of the strap 1 are attached in separated relation, and so that with an end of said lever in fulcrum engagement or bearing upon the article, a swing of the lever will effect the required frictional engagement of the strap 1 with the perimeter of the article to either hold the same against forcible rotation, or to forcibly rotate the same, as desired. The general construction so far described is old and no claim to the same is herein made.

A material part of the invention comprises a bearing shoe 3 of a concavo-convex plate form, having at its midlength pivot ears 4 for the pivotal attachment of one end of the operating handle or lever 2. One end

of the flexible strap 1 extends along the concave face of the arcuate shoe 3, thence around the forward edge or toe 3' of the same, with the terminal portion of the strap attached to the convex back, or face of the shoe by a rivet or like fastening means. Such construction provides a contacting surface for the shoe with the article engaged, of a soft nature throughout its width and length, with an entire avoidance of any hard portions liable to mar or break the article operated on.

The attachment between the strap 2 and shoe 3, above set forth, is adapted to permit a slight but free shiftable contact laterally, between the parts in the attainment of the function above set forth.

To the other end of the strap 1, an orificed plate or buckle 5 is attached, and to such end is formed with a receiving slot 7' for a loop 6 on said end of the strap. Said plate or buckle is also formed with a orifice 7 in right angle relation to the slot 7' aforesaid, and adapted to engage around the shank of the lever 2 and have holding engagement therewith at a point removed from the fulcrum point of the lever and preferably by engagement in one of a series of notches 8 formed along the length of the lever or handle 2, as shown.

Where the wrench is intended for use on section of tubing or like connected articles, the plate or buckle 5 has separable connection with the end of the strap 1 by means of an intermediate hook member 9 carried by the aforesaid loop 6 of the strap 1. With such construction the strap 1 disconnected from the lever 2, is made to encircle the article to be operated on, after which the strap is connected by the hook member 9 with the buckle 5 to complete the engagement of the parts with an article to be manipulated.

In the operation of the present implement, an initial movement of the operating lever 2 tends to force the portion of the strap 1 beneath the shoe 3 firmly against the perimeter of the article operated on to firmly bind such portion or end of the strap in stationary relation to the shoe 3 and the article, with a release of strain on the rivet or other fastening means of the strap to the shoe. In the further movement of the operating lever 2, the pull of the same upon the other end of the strap tends to tighten and bind the strap around the article and

effect a turning movement of the same in unison with the movement of the operating lever and its associated parts.

Having thus fully described my invention 5 what I claim and desire to secure by Letters Patent, is:—

In a strap wrench, the combination of an operating lever, a pliable work engaging strap having operative connection at its respective ends with said lever, a curved bearing plate, the convex side of which is provided at its mid-length with a fixed pivot ear for pivotal attachment to the operating

lever, the concave side of said plate affording free shiftable contact with the work engaging strap along the entire area of such concave side, and means for attaching an end of said strap to the convex side of the bearing plate to impose a bend in the strap in a passage around an end of said plate from the convex to the concave sides of the plate. 15 20

Signed at Chicago, Illinois, this 2nd day of December, 1925.

GEORGE SCHUSTARICH.
